UNITED STATES PATENT OFFICE.

CLARENCE S. ASHCRAFT, OF LOS ANGELES, CALIFORNIA.

ARC LAMP.

Application filed September 19, 1923. Serial No. 663,569.

This invention relates to arc lamps of the type provided with electrically operated mechanisms for feeding the electrodes towards the arc so as to compensate for the dis-
5 integration of the electrodes at the arc and thereby maintain a substantially constant arc during operation of the lamp. This invention is a continuation in part of my co-pending application, Serial No. 488,849, filed Au-
10 gust 1, 1921.

In my co-pending application there is described an arc lamp having electrically operated mechanisms for automatically maintaining a constant arc between the electrodes. 15 However, with the lamp of the co-pending application the electrodes must be manually adjusted by an operator when lamp is to be started so that the electrodes may be struck together and the arc formed. This compelled the 20 lamp to be positioned where it was within reach of the operator and had a further disadvantage that the striking together of the electrodes burnt away one side of the crater on the positive electrode with the result that 25 a dark spot could be seen in the radiated light which persisted several minutes after the arc lamp was started.

An important object of this invention is to provide a form of arc lamp which is entirely 30 automatic in operation and automatically and rapidly establishes the arc when current is supplied to the lamp and automatically adjusts the length of the arc to maintain a constant arc while the lamp is in operation, so 35 that resultant lamp may be operated from a locality or position spaced from the lamp.

By this invention not only is the necessity of manually striking the arc eliminated but the arc is rapidly established with the result 40 that the crater of the positive is not destroyed and the lamp starts immediately to send off a uniform ray of light.

Another object of this invention is to provide a more simple and economical mechanism for maintaining a uniform length of arc than the mechanism described in said co-pending application. More specifically one object of this invention is to provide a more simple means for interrupting the feeding 45 of the positive electrode when an interrupted feed is required and another object is to provide a means for making the negative feed continuous and always in the direction of the arc.

50 Another object of this invention is to provide an arc lamp in which the relation be-

tween the speeds at which the positive electrode and the negative electrode advance may be varied and controlled at will in the arc lamp so that a maximum efficiency of opera- 60 tion of the lamp may be attained.

It is found that the arc lamp hereinafter described may be economically operated on certain voltages with a continuous feed of both electrodes but that on certain other 65 voltages a more efficient operation is attained by interrupting the feed of one of the electrodes and preferably simultaneously changing the relation between the speeds at which the different electrodes advance. 70

Various other objects and advantages of this invention will be apparent from the description of the accompanying drawings and will be found in practice or use of the invention. In the accompanying drawings 75 I have illustrated a preferred example embodying this invention, but desire to be understood to the effect that while such preferred example incorporates the spirit of this invention, various changes may be made in 80 the form of the lamp without departing from the spirit of the invention.

In the drawings Figure 1 is a side elevation of this embodiment of the invention.

Fig. 2 is a rear elevation of mechanism 85 for interrupting feed of the positive electrode.

Fig. 3 is a side view of the mechanism shown in Figure 2.

Fig. 4 is a view looking in a direction parallel to the axis of the negative electrode of 90 the negative operating mechanism.

Fig. 5 is a section on the line 5—5 of Fig. 4.

Fig. 6 is a vertical section through the solenoid. 95

Fig. 7 is a diagram of the electrical connections.

Fig. 8 is a vertical section through the positive feeding mechanism and, 100

Fig. 9 is a section on the line 9—9 of Fig. 8. 100

In the drawings, the arc lamp is provided with a positive electrode generally indicated by A and a negative electrode generally indicated by B. The electrodes are arranged with one end of each electrode adjacent one end of the other electrode and the angle between the electrodes is preferably greater than a right angle and less than 135°. The positive electrode is preferably positioned with its axis parallel to the direction the light 110 is intended to be radiated. In order to produce a uniform intensity of arc it is necessary

to rotate the positive electrode, otherwise the crater of the positive electrode would become irregular in shape, elongated at one side more than the other. Under such conditions, the 5 direction at which the light was radiated would continually change.

It is likewise necessary to advance the electrodes of the lamp to compensate for the rate at which the electrodes burn or disintegrate. 10 A mechanism for producing both a continuous rotation of the positive electrode A and for advancing such electrode will now be described. The positive electrode A passes loosely thru a bushing 2 which encloses a portion 15 of the electrode. The bushing 2 is journaled by an anti-friction bearing 3 supported in a casting 4. The bushing 2 provides a circular plate 5 surrounding the electrode A, which plate 5 is provided with inwardly projecting brackets 6, each pair of brackets supporting a stud 7 which engages in radial slots 8 formed in the brackets, said slots permitting of radial movement of the studs relative to the axis of the drum. Adjacent ends of studs 20 7 are connected to each other by coiled springs 9, which yieldingly hold the studs 7 towards the axis of the drum. The opposite ends of the studs 7 are provided with clamps 10 held together by a screw 11. On each stud 7 between each pair of brackets 6 is rotatably mounted a spur gear 12. In the drawings two of such gears are illustrated, but it is understood that more or fewer of such gears may be employed if desired. The gears 12 engage 25 a spiral hoop gear 13 which is formed on the forward vertical face of a control member 14 which is rotatably mounted on the bushing 2.

The control member 14 provides a means for controlling the rotation of the gears 12 40 about their axes. Thus, if the control member 14 and the plate 5 mounting the gears 12 are both rotated at equal speeds the gears 12 will not rotate around their axis. If the rates of rotation of the control member 14 45 and the plate 5 are not equal then the spiral hoop gear 13 will cause the gears 12 to rotate. The gears 12 are adjusted by the screw 11 and tension of the spring 9, so that they engage the electrode A. Thus the rotation of the 50 gears 12 will cause the electrode A to move in an axial direction. The spiral hoop gear 13 is formed so that when the rate of rotation of the control member 14 is less than the rate of rotation of the plate 5 or bushing 2, the 55 gears 12 are rotated in a direction to cause the electrode A to advance the electrode towards the arc. The rotation of the bushing 2 and plate 5 is effected through a bevelled gear 15 secured to the rear end of the bushing 2 60 and driven from a shaft 16, carrying a bevelled gear 17 meshing with the gear 15.

The rotation of the control member 14 is 65 regulated by a gear 18 formed on the rear of said member. The gear 18 engages a pinion 19 secured to a horizontal shaft 20 journaled

in the casting 4. The shaft 20 is provided with a ratchet wheel 21 engaged by a pawl 22. The pawl is rigid with an arm 23 supporting a detent 24. The detent 24 is positioned with one end extending towards the back of the 70 bevelled gear 15 where it may engage one of a number of studs 25 projecting from the rear of said gear 15. (See Fig. 2.) The detent 24 has screw engagement with the arm 23 so that the detent may be screwed towards or away 75 from the studs 25 as the operation of the lamp may require. The pawl 22 and arm 23 as a unit are fixed to a shaft 26 which is journaled in the casting 4. 27 indicates a spring which yieldingly maintains the pawl 22 engaging 80 the ratchet wheel 21. By this construction the control member 14 is normally held from rotating with the bushing 2 due to the pawl 22, engaging said wheel 21, and thus the electrode A is normally continually advancing 85 towards the arc. Under certain conditions hereinafter described it is necessary to interrupt the feed of the electrode in which case the detent 24 is moved towards the studs 25 until the studs 25 on rotating will engage the 90 detent and pivot the detent 24 back, against the pressure of the spring 27, to permit the studs to pass. This releases the pawl 22 from the wheel 21 and the control member rotates with the rotation of the bushing 2, and the 95 advance of the positive electrode is interrupted. In the drawings there is shown three of the studs 25 which will cause the feed of the electrode A to be interrupted three times during each revolution of the bushing 2. Obviously more or less of the studs 25 could be provided if desired. The length of time each stud will interrupt the feed of the electrode A will depend upon the distance the detent 24 is screwed towards the studs. To support 100 the positive electrode A and its rotating and feed mechanism the casting 4 is secured to a horizontal support 28. Said support 28 is fixed to the top of a frame 29 by bolts 30 and electrically insulated from said frame by an insulating block 31 between the frame 29 and support 28. The frame 29 is bolted at its lower end to a lower frame 32 which serves to support certain parts of the negative feeding mechanism. 110

The rear end 33 of the frame 32 is turned vertically downward. Bolts 34 extending rearwardly from the frames 29 and 32 support vertical standards 35 to which an electric motor 36 is fastened. The motor 36 is provided with a worm 37 at the lower end of its armature shaft. A worm wheel 38 engages teeth of said worm and is fixed to a shaft 39 journaled in a housing 39' enclosing said worm and gear. The shaft 39 is provided with a flexible coupling 40 and terminates in a worm shaft section 41. The shaft 16, which drives the bushing 2, extends vertically downward in the lamp and provides a worm wheel 42 engaging the worm section 41. 130

From the foregoing it will be clear that operation of the motor 36 will produce a comparatively slow rotation of the electrode A, and also, when the pawl 22 is engaging the 5 wheel 21, will produce a rotation of the gears 12. The various gears are so proportioned relative to the speed of operation of the motor 36 that the speed at which the electrode A advances is just slightly faster than the speed 10 at which the electrode A is consumed, so that it is then possible with a minimum interruption of the positive electrode to bring the speed of advance of the positive electrode equal to the speed at which said electrode is 15 consumed. Exact adjustment of the detent 24 is not necessary since a further control of the speed at which the electrode advances is accomplished by automatic control of the speed of the motor 36 in a manner hereinafter 20 described.

The mechanism for feeding the negative electrode B will now be described. The vertical shaft 16 is provided at its medial portion with a bevelled gear 43 meshing with a bevelled gear 44 carried on a negative electrode operating horizontal shaft 45. The shaft 45 is journalled in the frame 29. 46 indicates a frame pivotally mounted on the lower frame 32. Said frame 46 provides a bearing 47 for 30 a shaft 48 which is inclined upward and joined by a universal joint 49 to the negative electrode operating shaft 45. The negative electrode is held by a clamp 50 extending from a carriage 51. The carriage 51 is adapted to 35 slide along two parallel rods 52 secured together by blocks 53 at their ends, the carriage 51 having tubular slides 54 telescoped over the rods. Journalled at its ends in the blocks 53 is provided a worm shaft 55 having a bevelled gear 56 meshing with a bevelled gear 57 fixed to the inclined shaft 48. The upper block 53 is bolted to a flange 58 extending from the bearing 47 thus supporting the negative electrode B on the pivoted frame 46. The 45 carriage 51 is provided with a toothed catch 59 which normally engages the worm shaft 55 to feed the carriage 55 and electrode B upon rotation of the shaft 55.

The catch 59 is preferably fixed to a bar, 50 such as 60, which is pivoted to the carriage at one end and the other end is yieldingly urged towards the worm shaft 55 by a spring 61, so that while normally the catch is in engagement with the shaft 55 the catch may be 55 released to manually shift the electrode along the rods 52.

Below the frame 32 is secured a solenoid 62 which provides an automatic means for striking the arc when operation of the lamp is to 60 be started. The solenoid comprises an electro-magnet 63 having an armature 64. The armature 64 is fixed to an arm 65 provided by the pivoted frame 46 and is pressed against a pin 66 engaging a coiled spring 67 set in the 65 front end of the solenoid. 68 indicates a bolt

which may be adjusted to vary the pressure exerted by the spring 67 through the pin 66 upon the armature 64.

The electro-magnet 63 is connected to the mains so that the current sent through the 70 electro-magnet 63 will draw the armature 64 which will tend to cause the frame 46 to pivot upward and strike the positive electrode A.

Referring to Fig. 7 the electrical wiring of the lamp is shown. The negative supply 75 main 70 connects with a ballast resistance 71 from which current is supplied to the negative electrode B being connected to the clamp 50 holding the negative electrode. The positive main is connected to the positive electrode A 80 through a ribbed conical contact member 72 enclosing the electrode A near the arc. The electro-magnet 63 and the motor 36 are each shunted directly across the arc. By this arrangement the voltage impressed on the arc, 85 the electro-magnet 63, and the motor 36 is equal at all times, and since the arc, electro-magnet, and motor, are each in series with the resistance 71 any change in the resistance across the arc will change the voltage impressed across the electro-magnet 63 and motor 36.

When the arc lamp is to be operated the current is first switched on. At the time the current is turned on the current cannot flow 90 across the gap between the electrodes and start the arc unless the electrodes are first struck together. This striking of the electrodes is effected by the solenoid. The electro-magnet 63 of the solenoid is constructed so that when the lamp is in operation the current through the magnet 63 is insufficient to draw the armature 64 into the magnet and pivot the electrode B up to strike the electrode A. Before the arc is struck, however, a much larger current is sent through the electro-magnet 63 due to the high resistance of the gap between the electrodes, and under such conditions the electrode is rapidly forced upward to strike the arc. When the electrodes strike together the 100 resistance to travel of the current through the electrode path becomes practically zero and accordingly the current through the electro-magnet 63 becomes very low permitting the electrode B to immediately drop back from 105 electrode A.

The motor 36 then rotates at a speed proportional to the voltage across the arc and advances both electrodes at a rate to compensate for the disintegration of the electrodes. Thus if the speed of the electrodes becomes insufficient to equal the rate of consumption of the electrodes the resistance across the arc will increase, producing a higher arc voltage, this causes a greater current to be sent through the motor and accordingly the same will speed up, and likewise when the speed at which the electrodes advance becomes too rapid the length of the arc will decrease, resulting in a decrease in 110 115 120 125 130

the resistance across the arc lowering the arc voltage and less current will then flow through the motor and the speed of advance of the electrodes will be retarded.

5 However, in cases where a great variation in the voltage on the mains may occur the motor 36 may not be able to maintain the arc constant with both the feeds of the negative and positive electrodes continuous. In such 10 cases it is preferable to fix the pitch of the hoop gear 13 so that the positive electrode will normally feed slightly faster than the electrode is consumed and adjust the feed of the positive electrode with the interrupting 15 mechanism. However, it is to be remembered that continuous feed of the positive electrode produces the most uniform arc, and that when the feed must be interrupted at short intervals, the time during which the feed is 20 interrupted should preferably be less than the time during which the electrode is feeding toward the arc.

I have found that this manner of feeding the positive electrode enables the arc lamp 25 to burn as long as five to ten times the period of time that an arc lamp, in which the positive electrode is jerked towards the arc and the periods of interruption greatly exceed the periods during which the positive 30 electrode is being fed, can be burned without requiring attention from the operator.

Other advantages of this invention are that the lamp is entirely dependable in operation, electrodes of varying diameters may be employed, the lamp is easy to operate, simple and economical in construction.

I claim:

1. In an arc lamp having a positive electrode, a negative electrode, and means for 40 advancing the electrodes, the combination of: an arc striking means comprising a negative electrode carriage so disposed as to normally hold said negative electrode separated from said positive electrode by the weight of 45 said carriage; and electro-magnetic means operative by the throwing on of the arc circuit for striking said negative electrode, the striking of the arc being effective to reduce the 50 strength of the pull of said electro-magnet whereby the weight of the carriage will cause it to fall back to normal operating position.

2. In an arc lamp having a positive electrode, a negative electrode, and means for 55 advancing the electrodes, the combination of: an arc striking means comprising a negative electrode carriage so disposed as to normally hold said negative electrode separated from said positive electrode by the weight of said 60 carriage; electro-magnetic means operative by the throwing on of the arc circuit for striking said negative electrode against said positive electrode; and a compression spring adapted to assist in return of the carriage to 65 normal operating position.

3. In an arc lamp: an electrode holder; an electrode supported by said holder; means for rotating said holder on the longitudinal axis of said electrode; means carried by said holder adapted to revolve therewith and to 70 be rotated for advancing said electrode; a spiral gear mounted on and adapted to rotate with said holder and adapted to rotate said last named means when its own rotation is retarded; and means for periodically retarding the rotation of said gear.

4. In an arc lamp; an electrode holder; an electrode supported by said holder; means for rotating said holder on the longitudinal axis of said electrode; means carried by said holder adapted to revolve therewith and to 80 be rotated for advancing said electrode; a spiral gear mounted on and adapted to rotate with said holder and adapted to rotate said last named means when its own rotation is 85 retarded; and means for periodically retarding the rotation of said gear, the last mentioned means comprising a first gear secured to said spiral gear, a second gear adapted to 90 engage said first gear, and a pawl adapted to engage said second gear and to be moved out of engagement therewith by the rotational movement of said holder.

5. In an arc lamp: an electrode holder; an electrode supported by said holder; means for 95 rotating said holder on the longitudinal axis of said electrode; means carried by said holder adapted to revolve therewith and to be rotated for advancing said electrode; a spiral gear mounted on and adapted to 100 rotate with said holder and adapted to rotate said last named means when its own rotation is retarded; and means for periodically retarding the rotation of said gear, the last mentioned means comprising a first gear secured to said spiral gear, a second gear adapted to 105 engage said first gear, a pivoted pawl adapted to engage said second gear and to be disengaged therefrom, a stud carried by said holder, a detent secured to said pawl and adapted to be moved by said stud, whereby said pawl is moved out of engagement with said second gear.

6. A combination as described in claim 5 in which said detent is adjustable.

7. In an arc lamp: an electrode holder; an electrode supported by said holder; means for rotating said holder on the longitudinal axis of said electrode; means carried by said holder adapted to revolve therewith and to be rotated for advancing said electrode; a spiral gear mounted on and adapted to rotate with said holder and adapted to rotate said last named means when its own rotation is retarded; means for periodically retarding the rotation of said gear, the last mentioned means comprising a first gear secured to said spiral gear, a second gear adapted to 120 engage said first gear, a pivoted pawl adapted to engage said second gear and 125

to be disengaged therefrom, a stud carried by said holder, a detent secured to said pawl and adapted to be moved by said stud, whereby said pawl is moved out of engagement with 5 said second gear; and means for returning said pawl into engagement with said second gear.

8. In an arc lamp: an electrode holder; an electrode carried by said holder; means for 10 advancing said electrode in said holder; and means actuated by said holder for periodically interrupting the action of said means for advancing the electrode, said last named means including means for varying the period of duration of said interruptions.

9. In an arc lamp: an electrode holder; means for rotating said holder; means ac-

tuated by the rotation of said holder to advance an electrode disposed therein; and means actuated by said holder periodically relative to the rotation thereof to interrupt 20 said electrode advancing means.

10. In an arc lamp: an electrode holder; means for rotating said holder; means actuated by the rotation of said holder to advance 25 an electrode disposed therein; and means actuated by said holder periodically relative to the rotation thereof to interrupt said electrode advancing means, the periodicity of the actuation of said last mentioned means being adjustable.

Signed at Los Angeles, California, this 31st day of July, 1923.

CLARENCE S. ASHCRAFT.
